UNITED STATES PATENT OFFICE.

JOHN L. McBEE, OF MANSFIELD, OHIO, ASSIGNOR TO REAM-McBEE COMPANY, A FIRM DOMICILED IN MANSFIELD, OHIO, AND COMPOSED OF HARRY M. REAM, JOHN L. McBEE, AND EDWIN O. TOWNSEND.

DESIGN FOR A MONUMENT.

44,376.

Specification for Design.

Patented July 22, 1913.

Application filed April 29, 1913. Serial No. 764,447. Term of patent 7 years.

To all whom it may concern:

Be it known that I, JOHN L. McBEE, a citizen of the United States, residing at Mansfield, in the county of Richland and State of Ohio, have invented a new, original, and ornamental Design for Monuments, of which the following is a specification, reference being had to the accompanying drawing, forming part thereof.

The figure is a perspective view of a monument, showing my new design.

I claim:

The ornamental design for a monument, as shown.

JOHN L. McBEE.

Witnesses:

KATHARINE MCKENNA,
RALPH M. HALL.
